UNITED STATES PATENT OFFICE

LUCY COTTON AMENT, OF NEW YORK, N. Y., NOW BY JUDICIAL CHANGE OF NAME
LUCY COTTON THOMAS

HOLDER FOR LIP STICKS AND THE LIKE

Application filed September 25, 1929. Serial No. 395,096.

My present invention relates to improvements in holders for lipsticks or the like.

An object of the invention is the provision of means for limiting the projecting movement of the lipstick or the like from the casing.

A further object is to provide a structure wherein the enclosing means for the end of the lipstick will not engage the sides of the stick in closing.

Another object is to provide means whereby the lipstick may be moved longitudinally of the holder only when the enclosing means are closed, the enclosing means limiting the outward movement of the stick in the holder.

Another object is the provision of end enclosing means on the casing comprising caps or cover members hinged to the casing and held in closed position by a surrounding sleeve and under spring tension by reason of their inherent resiliency causing them to fly open when said sleeve is withdrawn, without the use of springs at the hinges.

Another object is to provide a guiding pin on the casing extending through a slot in the sleeve and holding the sleeve and casing in proper circumferential relation to enable operation of the hinged covers by said sleeve.

A further object is to provide means facilitating one hand operation comprising a button on said sleeve in spaced relation to a button on the end of said guiding pin enabling them to be spread apart by the pushing of a finger or thumb between them to initiate the upward closing movement of the sleeve on the casing.

A still further object is to provide hinged covers with portions cut away and reinforced to secure strength without abrupt points, corners, or edges when opened to expose the stick for use.

Another object is to provide a flange on the tops of the closure members adapted to form with the upper edge of the sleeve an effective enclosure for the contents of the casing.

Other objects will appear hereinafter, the invention consisting in the features, combination, and arrangement of parts hereinafter described and particularly pointed out in the claims.

Referring to the drawings:

Figure 1 is an elevation of an improved lipstick holder in closed position, the sleeve being in section and the cam projections being engaged by the sleeve.

55

Fig 1a is a plan view of the sleeve only.

Fig. 2 is a similar view showing the holder of Fig. 1 in open position with the lipstick exposed for use, the cam projections on the closure members being shown in engagement with the withdrawn sleeve.

60

Fig. 3 is a sectional elevation of a holder in which the cover members have spring cams.

Fig. 4 is an elevation of the form of hinged cap or cover shown in Fig. 3.

65

Fig. 5 is a sectional view of the lower part of my improved holder showing a preferred form of locking means to prevent feeding the stick outwardly as soon as the sleeve is started on its downward movement on the casing to open the cover members and expose the stick, while permitting movement of the stick feeding means when the covers are in closed position and the sleeve is in uppermost position.

70

Fig. 6 is a view of the inner lipstick operating barrel provided with a peripheral series of short longitudinal grooves or teeth to cooperate with the locking detent shown in Fig. 5.

75

Figs. 7 and 8 are front and side elevations respectively of the holder with the covers removed from the top of the casing, and showing the guide pin and slot and the supplementary finger piece or button to cooperate with the guide pin button in enabling the ready initiation of upward movement of the sleeve to close the cover members.

80

Fig. 9 is a view of a modified form of locking means.

85

Figs. 10 and 11 are views of further modifications of the hinged cap structure.

90

In the drawings, 1 represents the casing of my improved holder for lipsticks or the like, in which is rotatably mounted the barrel 2 for controlling the stick or other contents and moving it longitudinally of the casing to project the same for use. The specific structure whereby the rotary motion of the barrel moves the stick longitudinally of the casing is

95

100

not shown or described as it is well known in the art and constitutes no part of the present invention. The barrel 2 has a knurled lower end 2a providing a bottom for the holder casing and providing a handle for operating the same.

Hinged to the upper edge of the casing at 13 and 14 are closure members 3 and 4 controlled by sleeve 5 slidably mounted on the 10 casing 1. The sleeve 5 hugs the casing except at outstanding portions 6 and 7 where it is enlarged to clear the hinges 13 and 14 and to engage the cam portions 10 and 11 of the closure members 3 and 4 to control and move 15 the closure members to closed position upon upward movement of the sleeve.

The closure members 3 and 4 as shown in Figs. 1, 2, and 3 are cap or hood shaped members having top portions 3a and 4a meeting 20 on a line 12 to form the closure, and being adapted to swing back and down alongside the casing.

Cam projections 10 and 11 are formed in any suitable way and may be formed by 25 building up the wall as shown in Figs. 1 and 2 or may be merely formed by denting the wall, causing it to be bulged on the outside, the metal of which the caps 3 and 4 are made being such that it will have sufficient inherent 30 resiliency to cause the cap closures to fly to open position when the sleeve is withdrawn, the cam projections being held under stress when the sleeve is moved to upper position engaging them.

In Fig. 2 cam projections 10 and 11 are shown in engagement with the withdrawn sleeve 5. The cams 10 and 11 shown in Figs. 1 and 2 are not spring members, but the inherent resiliency of the metal of which the 40 closures are made and the compression to which the closures are subjected by the sleeve when closed as in Fig. 1, serves to cause the closures to fly to open position upon withdrawal of the sleeve. The hinges 13 and 14 45 may be provided with springs 15, as shown in Figs. 1 and 2.

The cams 10 and 11 are disposed on the wall of the closure members 3 and 4 between the tops thereof and the hinges.

The cams are so formed and disposed that the upper edge of the sleeve is always in contact with some portion thereof whether the sleeve is advanced or withdrawn, and the cams are of such shape as to enable quick and 55 effective closing of the closure members when the sleeve is moved upwardly.

As shown in Figs. 1, 2, and 3, the caps 3 and 4 comprise top portions 3a and 4a having outwardly extending flanges 3b and 4b, and 60 depending skirt or wall portions 3c and 4c provided with the cams 10 and 11 and hinged to the casing at 13 and 14. The skirt portions 3c and 4c are cut away to remove all 65 projecting corners so that as shown in open position in Fig. 2, there are no projections

above the hinge point to interfere with the use of the contents.

The flanges 3b and 4b are of such extent that when the sleeve is moved to upper position, the upper edge thereof will approximately meet the outer edge of the flange, thus entirely enclosing the contents and enabling the skirt or wall portions 3c and 4c to be cut away as desired for the purpose described without exposing the contents.

Referring to Figs. 3 and 4, a preferred form of spring cam 10' and 11' is shown which is of such resilient character as to do away with all necessity of providing supplementary springs at the hinges. There are 80 no springs at the hinges in Figs. 3 and 4. A preferred construction of spring cam 10' and 11' is shown in Figs. 3, 4, and 11, in which the spring cam comprises an outwardly bowed strip of the wall of the closure members formed by slitting the wall vertically by spaced slits and then bowing out the strip portion between the slits.

In Fig. 11 the spring cam 10' is formed in the same way, the skirt or wall portion of 90 the cap being further reduced and provided with a reinforcement bracket 16 bracing the inner side of the wall and the under side of the top.

In Fig. 10, a modification is shown in which the wall portion consists of a single relatively narrow strip bowed to form the spring cams.

Figs. 5 and 6 show a construction of my 100 improved lipstick holder which prevents longitudinal projecting movement of the lipstick by the preventing rotation of the barrel 2 when the sleeve 5 is started downwardly from its uppermost position to open the closures while permitting said movement when the sleeve is in uppermost position with the closures shut.

This structure comprises a spring detent 110 17 secured to the casing and depressible through a slot 18 in the casing into engagement with the barrel 2. The spring detent 17 is secured at its lower end to the casing below the slot 18 and extends upwardly along 115 said slot to the point defining the upper position of the lower end of the sleeve. The detent has a cam 19 formed on its outer edge and is adapted to be engaged by initial downward movement of the sleeve to depress it through said slot and into frictional engagement with the barrel 2.

The barrel may be provided with a circumferential series of spaced vertical teeth 20 providing recesses therebetween for the interlocking reception of a toothed projection 21 on the detent 17.

By this construction, the closed cover members provide a limiting stop for the upper end of the contents as projected by the rotation of the barrel 2 with the sleeve in upper 120

position. This provides a usable portion of the contents when the covers are opened.

Upon initiating downward movement of the sleeve, the detent is immediately actuated to lock the barrel to the casing and to prevent movement of the contents either outwardly or inwardly until the sleeve is again advanced about the detent to close the covers. The detent remains depressed and the barrel

10 remains locked for all positions of the sleeve below its uppermost position.

A modified form of barrel locking arrangement is shown in Fig. 9 in which the barrel handle 2a is provided with a serrated 15 or toothed upper edge to cooperate with the serrated or toothed lower edge of the sleeve when the sleeve is in lowermost position, to lock the sleeve to the barrel. This locks the sleeve, barrel, and casing all together by 20 reason of the casing being provided with a pin 21 passing through a guide slot 22 in the sleeve and preventing relative rotation or circumferential misalignment of the sleeve and casing as shown in Figs. 7 and 8.

25 Referring further to Figs. 7 and 8, a finger button or knob is shown on the sleeve at 23 in such relation to the pin 21 on the casing when the sleeve is down, as shown, that a finger or thumb of one hand is to be forced between 30 the two and thus upward closing movement initiated in one hand manipulation of the device.

The importance of the guide slot 22 on the sleeve and headed pin 21 on the casing moving in the slot and maintaining the sleeve and casing against circumferential misalignment is apparent from the need of maintaining the outstanding portions 6 of the sleeve in exact alignment with the hinged cap members 40 3 and 4.

I do not desire to limit myself to the exact construction shown as it will be apparent that modifications may be made within the scope of the invention.

45 I claim:

1. In combination, a container casing, closure means extending above said casing a sufficient distance to permit a usable portion 50 of the contents of the casing to be projected beyond the upper edge of the casing and against said closure means, and means to project said contents from the casing against the closure means when the latter is in closed position to thus determine the extended position of said contents, and means to prevent movement of said contents relative to the casing when the said closure means are in open position.

55 2. In combination, a casing, closure means at one end of the casing, said closing means having spring portions in the walls thereof, and releasable means engaging said spring portions for holding the closure means in closed position under stress of said spring

portions whereby when released, said closure means will open automatically.

3. A container having a swinging closure at one end, said swinging closure having a spring wall, and means on the exterior of the container for holding the swinging closure in closed position under stress of said spring wall, said spring wall operating automatically to open the container upon withdrawal of the holding means.

75 4. In combination, a casing, closure means comprising two members pivotally mounted at opposite sides of the casing, said members each having an outwardly bowed spring portion in its wall, a sleeve slidable on the exterior of the casing for holding the swinging closure members in closed position against the force of said spring portions, said springs operating automatically to open the container upon withdrawal of said holding sleeve.

80 5. Apparatus according to claim 1 in which said closure means are controlled by a sleeve slidably mounted on said casing holding said closure means closed when moved to upward position on said casing and releasing said closure means to allow them to open when moved downwardly, said contents projecting means including a barrel rotatable within said casing and having a closed bottom forming a bottom for said casing and a handle for turning, said barrel having near its lower end a peripheral series of teeth providing a plurality of notches therebetween, said casing wall having a slot therein near its lower end and a spring detent fixed in said casing wall and movable in the slot, said detent normally protruding outwardly from said slot beyond the casing wall and having a portion disposed in said slot in horizontal alignment with said series of teeth on the barrel, said detent having its upper free end at the uppermost position of the lower end of said sleeve, said sleeve upon being started downwardly from its uppermost holding position depressing said detent to cause it to engage said notches between the teeth and lock the barrel and casing against relative rotation.

lock it against movement relative to the casing.

8. In combination, a container casing, closure means secured to the upper end of the casing, a sleeve on the casing movable upwardly to close the closure means and downwardly to release the same, means to prevent rotary movement of said sleeve on said casing, a member rotatably mounted within the casing for moving the contents longitudinally of the casing, said member having an enlarged operating handle portion extending downwardly beyond the lower edges of the casing and laterally beyond its walls and provided with an upwardly facing serrated edge, said sleeve having a serrated lower edge adapted when in lowermost position to engage the serrated edge of said member to lock said sleeve and member against relative rotation.

20 9. In combination, a casing, closure means hinged to the upper end of the casing, a sleeve on the casing movable upwardly to close the closure means and downwardly to release the same, said sleeve having outstanding portions at its opposite sides in alignment with said hinged closure means to engage and actuate the same, and means to prevent rotary movement or misalignment of said sleeve on said casing comprising a slot in said sleeve and a headed pin on said casing projecting through the slot in the sleeve.

10. Apparatus according to claim 9 in which said sleeve is provided near its top with a finger button between which and the said headed pin a finger is to be forced to initiate the upward movement of the sleeve on the casing in one-hand manipulation of the device.

40 11. In combination, a container casing, closure means pivotally mounted at the upper edge of said casing and adapted to swing back and down alongside the casing, said closure means comprising cap-shaped members the tops of which form the halves of the closed top, said cap shaped members each having a depending wall portion extending downwardly from its top and pivotally connected to the casing, an outwardly extending flange surrounding said split top, and a sliding sleeve on the exterior of the casing for controlling the closure means and for holding the same in closed position, said sleeve being adapted to move to uppermost position to close the hinged members with its upper edge in close proximity to said flange.

12. Apparatus according to claim 11 in which said wall portions of said cap members comprise a relatively narrow portion reinforced by bracket enlargement between the under side of the top and the inner side of the wall.

13. Apparatus according to claim 11 in which said wall portion is cut away on each

side from said top near the ends of the diametrical meeting line of the top to the pivotal connection to remove all upstanding projections when the cap members are swung to open position.

14. In combination, a container casing, closure means pivotally mounted at the upper edge of said casing and adapted to swing back and down alongside the casing, and a sliding sleeve on the exterior of the casing for controlling the closure means and for holding the same in closed position, and cam means on the closure means between the top of the closure means and the pivotal connection to the casing, the upper end of said sleeve always contacting some part of said cam means irrespective of the position of said sleeve on the casing.

In testimony whereof, I affix my signature.

LUCY COTTON AMENT.
